UNITED STATES PATENT OFFICE

111,502

DESIGN FOR A TEXTILE FABRIC OR SIMILAR ARTICLE

Arthur Wortman, West New York, N. J., assignor to Sterling Textile Printers, Inc., New York, N. Y., a corporation of New York

Application April 27, 1938, Serial No. 76,765

Term of patent 3½ years

To all whom it may concern:

Be it known that I, Arthur Wortman, a citizen of the United States and a resident of West New York, county of Hudson, and State of New Jersey, have invented a new, original, and ornamental Design for a Textile Fabric or Similar Article, of which the following is a specification, reference being had to the accompanying drawing, forming a part thereof, wherin:

The figure of the drawing is a face view of a piece of textile fabric, showing one complete design unit.

The characteristic feature of my design resides in the stemmed floral elements arranged as shown and consisting of uniform dots, so distributed and grouped as to present the appearance of a petit-point pattern.

I claim:

The ornamental design for a textile fabric or similar article, as shown and described.

ARTHUR WORTMAN.
